INVENTOR

George J. Winter,
BY
James J. Heetey & Co.,
ATTORNEYS

UNITED STATES PATENT OFFICE.

GEORGE J. WINTER, OF BUFFALO, NEW YORK.

HEEL.

Application filed March 5, 1923. Serial No. 623,014.

To all whom it may concern:

Be it known that I, GEORGE J. WINTER, a citizen of the United States, residing at Buffalo, in the county of Erie and State of New York, have invented new and useful Improvements in Heels, of which the following is a specification.

My present invention pertains to heels of the cushion or resilient type and it contemplates the provision of a heel that is inexpensive to produce, durable in construction and one that eliminates the expensive washers at present employed in heels now on the market.

The invention further contemplates the provision of a lower or outer lift for the heel that may be easily attached and as readily removed from old as well as new heels.

The invention further contemplates the provision in a resilient heel of a construction so arranged that the cushion or rubber tread portion of the heel will not shift at any time and notwithstanding the fact that said tread portion when worn at a certain point may be removed and replaced on the opposite shoe heel it is so attached to the lower lift that casual displacement of the tread portion is precluded.

The invention further contemplates the provision of a cushion heel so constructed and arranged that but a slight amount of rubber or analogous material is employed but notwithstanding this fact the tread is not robbed of its resiliency.

Other objects and advantageous characteristics of the invention will be fully understood from the following description and claim when the same are read in connection with the drawings accompanying and forming part of this specification, in which—

Figure 1 is a perspective view of the body portion of my novel heel.

Figure 2 is a similar view of the lower lift.

Figure 3 is a perspective view of the cushion tread portion of the heel.

Figure 4 is a sectional view taken longitudinally through the heel as assembled.

Figure 5 is a transverse section taken in the plane indicated by the line 5—5 in Figure 4 and looking in the direction of the arrow.

55 Similar numerals of reference designate

corresponding parts in all the views of the drawings.

The body portion 1 of my novel heel is constructed of leather or other similar material and is provided with the chamber 2, which provision is made in the interest of cheapness and lightness.

The lower leather lift 3 of the heel is preferably formed as a separate unit for a purpose hereinafter set forth in detail, and the said heel lift 3 is provided with the cut out portion 4 and surrounding the cut out portion 4 are nail holes 5, through the medium of which the lift or heel portion 3 may be secured to the body portion 1 by means of nails 8 that pass through the holes 5 and enter at the markings on the body portion 1. It will be manifest that the markings on the body portion 1 are made for the purpose of guiding the repair man in order that a smooth fit may be made when the lower lift 3 is placed face to face with the lower portion of the body incident to driving the nails 8 home. This lift is also, if desired, cemented to the bottom of the portion 1 prior to driving the nails.

The tread 6 is provided with a raised portion 7 that enters the opening 4 of the lift 3 and it will be noted that the lower or tread portion of the member 6 is tapered from the center toward the edges in order to increase the durability of said tread and cause same to wear evenly throughout and it will further be noted that the raised portion 7 is slightly decreased in depth so as to produce a slight intervening space between the lower end of the body portion 1 and the inner surface of the raised portion 7 whereby resiliency of the heel at the bearing point is assured.

When it is desired to equip a heel having the hollow chamber 2 with my novel improvements, the lower surface of the body portion 1 is marked with the nail guides and the lower leather lift having the nail holes 5 is placed on the body portion and the nails 8 driven through the lift into the body portion. The tread of resilient material is then cemented to the removable lower lift where it is prevented from shifting as well as being lost, not only by the cement but also by the raised projection 7 entering the cut out portion 4 of said lift. The lift being slightly increased in thickness in comparison with the projection 7

increases to an appreciable extent the resiliency of the tread as well as the heel as a whole.

Manifestly the tread portion 6 as well as the lower lift 3 may be manufactured as separate and distinct elements and because of this provision the said elements may be sold to a shoemaker and attached to any form of heels at present in the market. Moreover, they may be changed from one heel to another in view of the fact that many persons run their heels down at certain points and therefore the life of the heel is materially prolonged. The heel and especially the removable lift and tread are inexpensive to produce for the reason that they consist of but very thin elements and when necessary to discard old lifts and treads it is not incumbent to purchase the expensive and comparatively thick rubber tread portions now in use.

The curving of the heel assures even wear of the tread for the reason that the center or most resilient part of the heel will initially strike the ground and because of this fact and the further fact that no washers are employed the life of the heel is prolonged and the lightness as well as cheapness thereof will be readily apparent, and the cost of production by the elimination of approximately sixteen washers from the heel is material.

My novel improvements are adapted for use in connection more particularly with heels at present on the market and the idea of my invention is to place on sale a heel 6 of rubber or other resilient material having the raised portion 7 and the lift 3 having the opening 4. Regardless of the con-

dition of a heel it is simply necessary to remove one or more lifts of the heel, as occasion requires, and then nail the lift 3 on the bottom of the heel. These lifts are stamped and are sold as a part of the tread and obviates the necessity of producing a chamber in the base of a heel. This is quite an important item when consideration is given to the fact that it would be quite difficult to produce in the base of a heel a chamber to receive the projection 7.

Having described my invention, what I claim and desire to secure by Letters Patent is:—

A resilient heel comprising a main body portion, formed of wood or other similar material and tapered toward its lower end, a lift nailed on the lower surface of the body portion and formed of leather or other similar material and having an aperture in the direct center thereof; said aperture being cut so as to produce a wall that rests parallel with respect to the straight wall of the lift and further being cut to follow the contour of the remaining outer edge of the lift, a tread of resilient material cemented or otherwise securely retained on the lift and a resilient projection formed in the upper surface of the lift and of a shape to snugly rest in the aperture of the lift but slightly less thick than the lift; said tread surface being convex.

In testimony whereof I have hereunto set my hand in presence of two subscribing witnesses.

GEORGE J. WINTER.
